UNITED STATES PATENT OFFICE.

SAMUEL S. PINGREE, OF ST. LOUIS, MISSOURI.

DESIGN FOR AN ARTIFICIAL BAIT FOR TRAPS.

43,410.

Specification for Design.

Patented Dec. 31, 1912.

Application filed September 17, 1912. Serial No. 720,909. Term of patent 14 years.

To all whom it may concern:

Be it known that I, SAMUEL S. PINGREE, a citizen of the United States, residing at St. Louis, Missouri, have invented a new, original, and ornamental Design for Artificial Bait for Traps, of which the following is a specification, reference being had to the accompanying drawing, forming part thereof.

Figure 1 is a plan view of an artificial

bait for traps showing my new design. Fig. 2 is a side elevation of the artificial bait.

I claim:

The ornamental design for an artificial bait for traps, as shown.

SAMUEL S. PINGREE.

Witnesses:

F. R. CORNWALL,
S. J. PINGREE.
